Primary Examiner — Mary Ann Calabrese(74) *Attorney, Agent, or Firm* — Brinks Hofer Gilson & Lione(57) **CLAIM**

The ornamental design for an island display rack, as shown and described.

DESCRIPTION

FIG. 1 is a perspective view of the island display rack;
 FIG. 2 is a top plan view thereof;
 FIG. 3 is a bottom plan view thereof;
 FIG. 4 is a reduced scale front elevation view thereof;
 FIG. 5 is an enlarged right side elevation view thereof; and,
 FIG. 6 is a left side elevation view thereof.
 The broken lines are included for the purpose of illustrating environmental structure and form no part of the claimed design.
